UNITED STATES PATENT OFFICE.

FRANK M. FITCH, OF EAST HARTFORD, CONNECTICUT.

SAFETY DEVICE FOR OPERATING DAMPERS.

1,355,135.

Specification of Letters Patent. Patented Oct. 12, 1920.

Application filed January 23, 1919. Serial No. 272,638.

To all whom it may concern:

- Be it known that I, FRANK M. FITCH, a citizen of the United States, and a resident of East Hartford, in the county of Hartford and State of Connecticut, have invented certain new and useful Improvements in Safety Devices for Operating Dampers, of which the following is a specification.
- 10 My invention relates to the class of devices employed for operating the dampers of heaters of various sorts and especially those employed for heating dwellings, and an object of my invention, among others, is to provide a device of this class that shall be extremely simple in its construction, effective in operation, and especially one that shall obviate danger of excessive heating after a damper has once been opened.
- 20 One form of device embodying my invention and in the construction and use of which the objects herein set out, as well as others, may be attained, is illustrated in the accompanying drawings, in which—
- 25 Figure 1 is a diagrammatic view illustrating the construction and operation of my improved apparatus.
- Fig. 2 is a detail view illustrating a portion of the motor and its operation.
- 30 Fig. 3 is a detail view further illustrating the construction of the operating motor.
- Fig. 4 is a detail view, scale enlarged, illustrating the means for connecting the pendulum with the driving wheel of the
- 35 motor.
- Fig. 5 is a detail view, scale enlarged, illustrating the damper and the mechanism appurtenant thereto.
- Fig. 6 is a detail view, scale still further
- 40 enlarged, illustrating the means for holding the damper in its closed position, and for releasing it to permit it to open.
- Fig. 7 is a detail view, scale enlarged, illustrating mechanism for operating the
- 45 controller and operated by it, the controller being shown in edge view.
- Fig. 8 is a top plan view of the controller and connected parts.
- Fig. 9 is a detail view, scale enlarged over
- 50 Figs. 7 and 8, illustrating the controller catch and a cut-out appurtenant to the controller.
- Figs. 10, 11 and 12 are detail views illustrating the mechanism for retaining the
- 55 damper in its closed position and for releasing it to permit it to open.
- My improved apparatus may be attached to furnaces of various types, it having been found to produce extremely satisfactory results when used in connection with steam 60 heating furnaces in dwellings, and for this reason such a furnace is illustrated in the drawings herein in which the numeral 5 indicates a portion of a furnace having a damper 6 to control entrance of air to the 65 ash pit, this damper being of the flap type and located on the side of the furnace. The numeral 7 indicates a lever common to furnaces of this type and that is operated by means of steam pressure to regulate conditions attending the running of the furnace, and which lever in its operation is raised and lowered in a manner readily understood by those skilled in the art, and therefore, it will be understood that the apparatus thus 75 far described is not original with me.
- My improved apparatus comprises in its construction a safety device 8, styled in the claims herein as a controller that may be movably mounted to operate in various 80 ways, as herein shown this movement being provided for by pivotally attaching the controller at one end to a base 9 supported in any desirable manner, as by a post 10. The damper may be opened by various agencies 85 operated manually or otherwise, and whenever opened it is so connected with the controller that the latter will operate to close it under predetermined conditions as they arise.
- In the apparatus as disclosed herein a spring projected latch bolt 11 (see Fig. 9) is slidably mounted to engage the controller 8 and hold it in its "set" position, and the latter is raised to this "set" position by 90 means of a controller setting device 12 secured to a flexible member, as a cord or chain 13, that passes loosely through a hole in the controller so that it may have a limited movement independently thereof. The 100 setting device is of a size to prevent its passage through the hole in the controller, consequently when the cord is pulled upwardly, after it has moved to a limited extent independently of the controller the setting device 105 will engage the under side of the controller and move it upwardly to be engaged and held by the latch bolt 11. This bolt may be operated to release the controller at any predetermined time by mechanism variously arranged, a convenient means to this end, when the apparatus is used in connection with a

steam heating furnace, comprising a bolt actuating lever 14 pivotally attached at one end to the base 9 and operatively connected with the safety lever 7 and also connected 5 with the latch bolt 11 as by means of a flexible device 15, said bolt being housed in a stationary case 36. This arrangement also permits the damper to be left open to any desired extent by providing the cord 13 with 10 a number of catches 16 to engage a holder, as a hook 17, the cord being lowered to the desired extent after it has been operated to "set" the controller, and even to an extent to permit the damper to move to a closed 15 position if desired.

The opening of the damper as hereinbefore described, of course, increases the heat generated by the furnace, which operation, if allowed to continue, would raise the heat 20 to an uncomfortable degree and would also be a source of danger, and the controller, therefore, serves its purpose at such times by causing the damper to be closed under predetermined conditions as hereinbefore referred to.

The cord 13 is provided with extensible sections 18—18^a, one being located above the controller, preferably near the catches 16, and the other being located below the controller, springs being illustrated herein as the extensible elements. The section 18 will allow the cord 13 to "stretch" to permit the controller to move downwardly to close the damper when the controller is released.

The device thus far described provides means whereby the dampers in a furnace may be maintained in position to shut off the draft until such time as more heat may be required. The cord 13 may extend to rooms 35 to be heated by the furnace and to a convenient location therein, and when it is desired to increase the heat the damper may be opened by pulling up the cord sufficiently to set the controller, after which setting operation 40 one of the catches may be engaged with the holder 17 to retain the damper open to the extent required. When the heat has been raised to a predetermined degree the damper will be closed by release of the controller by the means herein shown or by any other suitable means, and I prefer to employ 45 a spring 77 to aid the movement of the controller when released. The damper may be held open by electrically released means to 50 be hereinafter described.

The invention thus far described relates to the safety mechanism comprising one part of my improved apparatus and that operates to close the damper before the fire has increased the heat unduly, and this is of special 60 advantage in connection with that part of my invention comprising time controlled apparatus for automatically opening the damper under predetermined conditions. 65 This apparatus comprises a retainer 19 (see

Figs. 10 and 11) that may be released in various ways and at the proper time to permit the damper to open. A satisfactory arrangement to effect this result comprises a pivoted lever 19 acting as said retainer, in 70 the construction shown this lever having a hook to engage a ring as on a cord 20 suspended from the damper 6. A damper trip 21 is pivotally mounted to engage the retainer and hold it in position to keep the 75 damper closed against a force exerted to open the damper. The operation of this trip may be controlled in various ways, an electrical apparatus being shown herein for accomplishing this purpose, this apparatus 80 comprising a damper opening magnet 22 adapted, when energized, to attract a damper trip release 23 in the form of a pivoted lever that underlies the end of the damper trip 21 when the latter is "set" and retains it in 85 this position to assist in holding the damper closed. The electric circuit for operating this magnet may be controlled in any suitable manner through the agency of a time piece 24, the electric current passing through 90 the positive wire 25 of a damper releasing circuit, extending, generally speaking, from one pole of a primary battery 26 to a contact 34 on the damper trip 21, thence to a contact on the damper trip release 23, 95 (when the parts are set to hold the damper) then through wire 33 to the magnet 22 and from said magnet by one section 27 of a negative wire to the time piece 24, and from thence by the other section 28 of the negative 100 wire to the other pole of said battery.

A satisfactory form of switch device comprises a switch bar releasing lever 29 held in "set" position by means of a key 30 of the alarm of the time piece 24, the other end of the lever engaging a spring pressed switch bar 31 to which the wire 27 is connected and having a contact to engage a contact to which the wire 28 is connected.

The mechanism thus far described provides means whereby the damper may be automatically opened at any predetermined time and whereby it may be closed to avoid too high a degree of heat within the furnace, the apparatus operating as follows:

Assuming that the damper is to be opened at a certain time in the manner above described before the rising hour, the cord 13 will be secured at its upper end, as shown in dotted lines in Fig. 1 of the drawings, 120 and the damper will be closed by engagement of the ring on the cord 20 with the hook on the retainer 19, the damper trip 21 being placed in contact with said retainer 125 and held in this position by means of the damper trip release 23, the parts being thus manually "set". The extensible section or spring 18^a will permit the damper to be closed as above described, without unnecessary strain upon the extensible section 18, 130

which strain may be caused, under certain conditions, by friction, caused by the arrangement of the cord 13 in extending it to places remote from the furnace. The switch 5 bar 31 will be moved against pressure of a spring 90 into engagement with the switch bar releasing lever 29 that will rest in contact with one side of the key 30, the alarm of the time piece 24 having been set for release 10 at say five o'clock. When the alarm is released the key in its turning movement releases the lever 29, which in turn releases the switch bar 31 and the spring of said bar throws it against the contact 32, closing the 15 circuit at this point and completing the electric circuit thereby energizing the magnet 22. The magnet is thus caused to swing the trip release 23 from engagement with the damper trip 21 allowing the latter to freely 20 move and thereby disengage the retainer 19 that is pulled upwardly by the opening movement of the damper which is caused by the tension of one or both of the extensible sections in the cord 13. When the retainer 25 is moved upwardly to a sufficient extent the ring on the cord 20 will be pulled from engagement with the hook on the retainer and the latter will fall and all parts will assume the position shown in Fig. 1 of the drawings, 30 (except that the damper will, of course, be open).

In the above operation it will be seen that an electric circuit has been established, and, further, that the circuit will be broken when 35 the damper trip and the damper trip release separate after the parts have operated as above described, it being understood that the parts will be suitably insulated in a manner that will be readily understood by those 40 skilled in the art so that current will pass along the course intended.

My improved apparatus comprises means for automatically opening the damper. In the device shown there is embodied spring 45 actuated mechanism of any ordinary and well-known construction located in a case 35 and including a pendulum rod 37 connected in any ordinary manner with said mechanism to have its movement accelerated there- 50 by and supporting a pendulum 38 having a pendulum trip 39 electrically controlled to make contact with a driving wheel 40 of a driving mechanism, said driving wheel being connected as by means of bevel gears 41 and 55 42 with a drum 43 adapted to receive a flexible connection as a cord 13^a attached to the cord 13 and forming a part of said cord 13.

A preferred means for controlling operation of the trip 39 is a thermostat T electrically connected with the primary battery 26. This thermostat may be of any well known construction and further and detailed description is, therefore, omitted herein. When the thermostat is set, say at 60 65 seventy-one degrees, to effect opening move-

ment of the damper the current passes by positive battery wire 45, having its end wound around the pendulum rod, from the battery 26 to a magnet 46, as shown in Figs. 1 and 3 of the drawings, and therefrom by 70 magnet wire 47, having its end wound around the pendulum, to a pawl operating magnet 48, through said magnet and by wire 49 to a make and break device in a case 36 (see the detail showing in Fig. 9) and including a terminal 84 adapted to make contact with a blade 85 movably mounted on a blade actuator 86 electrically connected by wire 87 with wire 50 that extends to and is connected with a make and break device at a 80 terminal 51, and through the circuit thus established, to said terminal 51 the latter being located in a case 88 placed in proximity to the damper 6. This last mentioned make and break device (see the detail showing in 85 Fig. 6) is operated by the damper at the conclusion of its opening movement and at the beginning of its closing movement, and it includes the terminal 51 coöperating with a blade 52 attached to a spring pressed make 90 and break member 53 positioned to be operated by the damper as above mentioned. The electric circuit, before the damper is raised to the position shown in dotted lines in Fig. 5, and when the blade 52, therefore, 95 is in contact with the terminal 51, passes from said terminal through the blade 52, to contact 55 and from thence by wires 54 and 55 through damper trip contact 56 and wire 57 to the thermostat and thence by wire 58 100 to the battery 26.

When the apparatus is set for opening operation of the damper by the time device, this circuit will be broken at the contact 56 and the thermostatic control will then be in- 105 effective.

In the operation of that part of the apparatus just described the energizing of the magnet 46 draws the trip 39 into contact therewith and the end of the trip is then in 110 position to strike the fingers 59 of the driving wheel 40, the end of said trip being made, flexible as by a pivoted, spring actuated section, which will be readily understood from an examination of Fig. 4 of the drawings, 115 this construction causing the wheel 40 to be rotated by the trip as the pendulum swings in one direction, the pivoted section of the trip yielding to permit it to pass the fingers as the pendulum swings in the opposite di- 120 rection. The trip is forced away from the magnet as by a spring 60. It will be understood that the pendulum is in continuous operation. The current also energizes the mag- 125 net 48 that draws a pawl 61 into contact with said magnet, this pawl operating against a ratchet wheel 62 having teeth formed in the usual manner and inclined toward and adapted to engage the pawl to prevent backward movement of the drum 43 130

as the cord 13 is wound thereon, a spring 44 (see Fig. 1) operating to draw the pawl away from the ratchet wheel when the magnet is deenergized. The pawl may be of any suitable construction having little friction by contact with the teeth of the ratchet wheel. As the damper 6 reaches its uppermost position, as shown in dotted lines in Fig. 6, the member 53 is operated to break the circuit; the magnets hereinabove described are deenergized; the trip 39 is withdrawn by its spring from the path of the fingers 59; the pawl 61 is withdrawn by its spring from engagement with the ratchet 62, and the drum is, therefore, free to unwind; a detent 63 snaps into holding position to retain the damper raised, and the opening operation of the damper ceases. The damper in its upward movement is arranged to encounter the damper opening detent 63 that may be in the form of a spring pressed latch bolt that is pressed back by the damper in its upward movement and that is pressed outwardly, when the damper has passed, into its path of downward movement to hold it in its raised or open position, as shown in Fig. 6 of the drawings.

In the operation above described should the make and break at 51 fail to operate upon the full opening of the damper the motor will continue operation to raise the controller and the circuit will, therefore, be broken at 84 when the controller 8 is fully closed, this closed position being determined by a stop 67. The object of the make and break at the controller is to provide for an emergency, namely, the failure of the make and break 51 at the damper to operate properly to stop the action of the driving wheels. When the controller 8 is closed the make and break at 84 shuts off the damper opening circuit.

The cord 13 is so adjusted that the full opening of the damper by the cord 13 does not fully close the controller 8. The damper cannot rise above the detent 63 except sufficiently to give easy play to movement of the detent and the damper is prevented from so rising by the contact of fixed stops 70 and 71. In the normal operation of this safety mechanism a spring 77 will always operate to swing the controller 8 to a wide open position, and it is, therefore, this controller that unwinds the drum 43 even though the damper remains open and supported by its detent 63.

If for any reason the cord 13 should be raised so as to completely close the controller 8 and hold the damper open while the thermostat was operating also, the lever 7 would withdraw the latch 11 in due season and release the controller 8. The thermostat being free to work would have energized, in a manner hereinafter described, a magnet 73 to withdraw the detent 63 and release the

damper and the controller would then compel the unwinding of the drum 43 in case the weight of the damper had failed to do so before.

A contingency, though remote, has been provided for, as follows:

Obviously should the battery give out when the damper is held open by the detent 63 the operation of the controller by the safety lever 7 and its consequent downward movement would release or "stretch" the cord 13 but the damper being held fast by the detent 63 could not close. Therefore, I introduce a small secondary battery 76 and establish for its operation the following circuit:

Wire 72 extends from one pole of said battery to a contact 79 in the case 36 adapted to be struck by a contact 80 on the bolt 11. A wire 68 extends from the contact 80 to a contact 66 arranged to engage blade 52, adapted to be moved into contact with a conductor 78 on the damper releasing magnet 73. A wire 74 connects said magnet with the opposite pole of said battery and also with the wire 75 that is joined to the wire 74. The effect of a prolonged connection between the contacts 79 and 80 owing to pressure on the levers 7 and 14 will be destroyed by the break between contact 66 and blade 52 when the damper moves from its open position.

When the damper is held in its open position, as hereinbefore described the thermostat, responding to the rising temperature, will establish a damper closing circuit from the battery 26 by wire 64 to wire 68, contact 66, blade 52, conductor 78 to the damper releasing magnet 73, through said magnet and by wire 74 to wire 55, contact 56, wires 57 and 75 to the thermostat and wire 58 to the battery. The member 53 is spring pressed into the path of movement of a roller on the damper, as shown in Fig. 6 of the drawings. The damper release 73 as herein shown is in the form of a solenoid, the core of which is rigidly secured to the detent 63. The electric current thus established, energizing the damper release 73 withdraws the detent 63, permitting the damper to fall to its closed position, in which movement it breaks the circuit between the blade 52 and the contact 66 and between said blade and the conductor 78. In falling, however, the damper reestablishes a connection at the terminal 51 and blade 52, so that the flow of electric current may again take place when the thermostat makes an electric connection at the terminal therein of the wire 57, when the action hereinbefore described will again take place to open the damper.

In accordance with the provisions of the patent statutes, I have described the principles of operation of my invention, together

with the apparatus which I now consider to represent the best embodiment thereof; but I desire to have it understood that the apparatus shown is only illustrative, and 5 that the invention may be carried out by other means.

In the installation of my improved apparatus the conditions with respect to the kind of heating device, the relative location of 10 parts of my improved apparatus with respect to such heating device, and to each other, &c., the arrangement herein shown will not be strictly adhered to, but will be 15 changed as the conditions may suggest or as may be desired, and this is especially true with respect to the mechanical arrangement for opening the damper, and I do not, therefore, limit my invention to any special mechanical arrangement for accomplishing this 20 purpose, as any type of motor employing power to open the damper may be utilized and yet be within the spirit and intent of the invention.

I claim—

25 1. A damper operating device including a controller, means for retaining the controller in a "set" position, means for releasing said retaining means, a damper, a connection extending from the damper 30 through the controller and loosely engaging the latter, said connection comprising a resilient member, a stop on said connection to engage the controller for raising purposes, means for holding the damper in a closed 35 position, and means for releasing said retaining means.

2. A damper operating device including a controller, a damper, means for "setting" the controller, said means extending loosely 40 through the controller and being connected to the damper, a stop on said "setting" means to engage the controller for setting purposes, means for securing said "setting" means in "set" position, means for holding 45 the controller in "set" position, and means for releasing said holding means.

3. A damper operating device including a controller, a damper, a setting device passing loosely through the controller and 50 attached to the damper, a stop on said set-

ting device to engage the controller to move it to "set" position, means for securing the setting device, a resilient member comprised in said setting device, means for holding it in "set" position, and means for releasing 55 said holding means.

4. A damper operating device including a controller, a damper, a setting device extending loosely through the controller and secured to the damper, a resilient member 60 comprised in said setting device between the controller and damper, a stop on said setting device to engage the controller, means for forcing the controller from "set" position, means for securing the setting device, 65 a resilient member comprising a part of the setting device near said securing point, means for retaining the controller in "set" position, and means for releasing said retaining means. 70

5. A damper operating device including a controller, means for retaining the controller in a closed position, means operated by a rise in temperature for releasing said retaining means, a damper connected with 75 the controller and supported in an open position, means exerting force upon the damper to open it, means for holding the damper in a closed position, and a time piece operatively connected with said holding means to release it for opening movement of the damper. 80

6. A damper operating device including a controller, means for retaining the controller in a "set" position, means operated 85 by a rise in temperature for releasing said retaining means, a damper, controller operating means extending loosely through the controller and connected with the damper, a stop attached to the controller operating 90 means to engage the controller for opening movement thereof, a resilient connection between the damper and controller, means exerting force upon the damper to open it, means for holding the damper in a closed 95 position, and a time piece operatively connected with said holding means to release it for opening movement of the damper.

FRANK M. FITCH.
